UNITED STATES PATENT OFFICE.

WILLIAM BLOCK, OF CHICAGO, ILLINOIS.

DESIGN FOR AN ARM-SUPPORTING BRACKET FOR LAMP STANDS.

Application filed December 7, 1925. Serial No. 15,674. Term of patent 3½ years.

To all whom it may concern:

Be it known that I, WILLIAM BLOCK, a citizen of the United States, residing at Chicago, in the county of Cook and State of Illinois, have invented a new, original, and ornamental Design for an Arm-Supporting Bracket for Lamp Stands, of which the following is a specification, reference being had to the accompanying drawing, forming part thereof.

The figure is a side elevational view of an arm supporting bracket, showing my new design.

I claim:

The ornamental design for an arm supporting bracket for lamp stands, as shown.

WILLIAM BLOCK.
